[57] CLAIM

The ornamental design for a call processor for a telephone system, substantially as shown and described.

DESCRIPTION

FIG. 1 is a top plan view of a call processor for a telephone system, showing our new design;

FIG. 2 is a bottom plan view thereof;

FIG. 3 is a front elevational view thereof;

FIG. 4 is a rear elevational view thereof;

FIG. 5 is a side elevational view thereof taken from the right side of FIG. 1;

FIG. 6 is a side elevational view thereof taken from the left side of FIG. 1; and

FIG. 7 is a perspective view thereof.

The showing of a portion of the cord in broken lines in FIGS. 1, 2, 3, 5, 6 and 7 is for facility of illustration.

FIG. 2

FIG. 3

FIG. 4
